C. BLAMFIELD.

TOX.

APPLICATION FILED JULY 15, 1918.

1,281,492.

Patented Oct. 15, 1918.

Inventor,

Charles Blamfield;

By
A. B. Lypham,
Attorney.

UNITED STATES PATENT OFFICE.

CHARLES BLAMFIELD, OF BOSTON, MASSACHUSETTS.

TOY.

1,281,492.

Specification of Letters Patent. Patented Oct. 15, 1918.

Application filed July 15, 1918. Serial No. 245,112.

To all whom it may concern:

Be it known that I, CHARLES BLAMFIELD, a subject of Great Britain, and a resident of Boston, in the county of Suffolk and Commonwealth of Massachusetts, have invented 5 certain new and useful Improvements in Toys, of which the following is a full, clear, and exact specification.

The object of this invention is the construction of a toy wherein there are parts 10 removably secured together, and which, while easily detachable, will remain united without danger of accidental disconnection, and will also be capable of a number of different angles of adjustment.

While the invention is capable of a wide range of applications, I have illustrated it as applicable to the movable parts of an animate object, as a horse whose head, neck, 20 legs and tail are represented as detachably united by the device constituting one feature of my invention, the curved joining surfaces constituting another important feature.

In the drawings forming part of this 25 specification, Figure 1 is a side sectional view of a toy embodying my improvements, the section being through the irregular line X—X in Fig. 2. Fig. 2 is an end view from the front, of the body portion of the toy. Fig. 3 is a side view of one of the legs of 30 the toy, showing the connecting device projecting therefrom. Fig. 4 is a side view of one of the connecting devices alone. Fig. 5 is an end view of the same. Fig. 6 35 is a perspective view of another form of the connecting device.

Referring to Fig. 1, the numeral 1 designates the body of the toy horse selected for illustration, 2 is the head, 3 is the neck, 4, 5, 40 6 and 7 are the legs, and 9 is the tail.

The preferable form of connecting device consists of a slender metal tube 10 having yielding material at its ends, such as the threads 11 shown in Fig. 4. It is more economical to construct the same by placing a 45 number of threads, or a length of tape, upon a small metal plate and then bending the latter into a slender tube tightly clutching the yielding material.

50 Or the connecting device may be made by simply bending over on itself a flat piece of sheet metal, and having it tightly clutching between its halves a length of tape 12, such flat pin 17 being illustrated in Fig. 6.

In each removable member a suitable hole 55 is made, as at 13, into which one of the connecting devices 10 or 17 is firmly secured. By having the yielding material at the inner ends as well as at the outer ends of the pins 10, 17, glue may be used for insuring their 60 firm anchorage in the holes.

Suitable perforations 14 are formed in the body 1 and in the outer portion of the neck 3 for the removable reception of the pins, 65 enough holes being provided to accommodate the pins of all the members, and as many more holes as there are different positions desired for each member. If, for example, it is desired to have the neck erect or drooping, three or more holes 14 are provided.

To give a perfect fit between a member and the body at each of the different radially disposed positions, the holes 14 should radiate from a single point, and the surface of 75 the body thereat should be curved concentric with such point of radiation, this curvature being convex, while the corresponding part of the member should be concaved to fit it.

For the neck and tail 3, 9, a single line of 80 holes is provided for each, as shown in Fig. 2, but for the legs the body 1 is formed with two lines of holes, as shown at the lower part of the body 1 in Fig. 2, one line for 85 one leg, and the other for the other leg.

In putting the parts together, all that needs to be done is to push the pins 10 into the holes which allow the desired positions, the threads or filaments 11 giving the friction which serves to retain the members together. The threads of course fold over the end of the tube 10 as the latter is thrust into a hole 14, and fill substantially all the space 90 between the tubular pin and the hole.

It frequently happens that in certain positions of the legs the feet do not all four contact with the support on which the horse is stood. Consequently I provide a small 95 wedge 15 for introduction between the support and the foot out of contact therewith, as shown in Fig. 1.

Although I have described the pin 10 as cylindrical, and show it in Fig. 5, I do not restrict myself to such form, as it may be 100 made flat as illustrated in Fig. 6, and a length of tape 16 used instead of the threads 11. The ends of the tape I prefer to glue

together against a side of the plate or pin 17. The operation, however, is substantially like that of the cylindrical pins, the tape giving the same frictional resistance to prevent the too-easy withdrawal thereof.

What I claim is:

1. The combination with two objects designed to be removably attached one to the other, of a pin projecting from one of the objects having yielding material attached to the projecting end, the other object having a hole for snugly receiving the pin.
2. The combination with two objects designed to be removably attached one to the other, of a tubular pin projecting from one of the objects, the pin having numerous filaments clamped therein and extending for a distance from its outer end, the other object having a hole for snugly receiving the pin.
3. The combination with two objects designed to be removably attached one to the other, each having a hole therein, of a pin having a mass of threads projecting from

each end and fitted to be thrust snugly into the respective holes.

4. The combination of two objects one of which has a cylindrically convex portion and the other a concave portion fitting the convex portion, the convex portion having a plurality of holes the prolongations of which would meet at the center of curvature of the convex portion, and a pin projecting from the concave portion and fitted to frictionally enter any one of the holes in the convex portion.

5. A connecting device comprising a pin having numerous threads extending from each end thereof.

6. A connecting device comprising a tubular pin having a mass of threads clamped within it and projecting from both ends.

In testimony that I claim the foregoing invention, I have hereunto set my hand this 13th day of July, 1918.

CHARLES BLAMFIELD.
